DESIGN FOR A BEVERAGE VENDING
MACHINE

George H. Hansen, Jr., Kansas City, Kans., as-
signor, by mesne assignments, to The Vendo
Company, Kansas City, Mo., a corporation of
Missouri

Application October 25, 1948, Serial No. 149,274

Term of patent 14 years

(Cl. D52—3)

To all whom it may concern:

Be it known that I, George H. Hansen, Jr., a citizen of the United States, residing at Kansas City, in the county of Johnson, and State of Kansas, have invented a new, original, and ornamental Design for a Beverage Vending Machine, of which the following is a specification, reference being had to the accompanying drawing, forming a part thereof.

Figure 1 is a front perspective view of a beverage vending machine, showing my new design; and

Fig. 2 is a side elevational view thereof.

I claim:

The ornamental design for a beverage vending machine, as shown.

GEORGE H. HANSEN, JR.
